ELECTRICAL NETWORK

Andrew Alford, New York, N. Y., assignor to
 MacKay Radio and Telegraph Company, New
 York, N. Y., a corporation of Delaware

Application March 22, 1935, Serial No. 12,451

4 Claims. (Cl. 178—44)

This invention relates to new and useful improvements in electrical networks and particularly in networks adapted for use with radio antenna circuits.

The main object of the present invention is to provide an impedance matching device for a transmission line interconnecting a high frequency radio transmitter and an antenna operable on more than one frequency.

In networks of this nature variable condensers and induction coils, or switching devices for selecting a suitable inductance or capacitance are usually employed. By means of such variable or switching devices the electrical constants of the network may be varied to suit the current frequency employed.

Such variable devices are expensive and are usually located at points remote from the operating personnel which makes their servicing and adjustment inconvenient. Remote control arrangements materially increase the cost of installation and operation.

In accordance with the present invention the use in such networks of variable or switching devices is completely obviated. Fixed impedance devices or networks are permanently associated with the line, each network having an impedance of precomputed value to match the load or antenna impedance to the surge impedance at a particular frequency and presenting a substantially infinite impedance at certain other frequencies.

In accordance with one feature of the invention, instead of the customary condensers and induction coils only straight wires are used as inductances, whereby the original cost of installation is reduced and the necessity of providing housings is eliminated. The straight wires may in all cases be in the form of concentric conductors or ordinary bare wires. Therefore, at the radio transmitting or receiving station, i. e., at points remote from industrial centers, inductances of the required values can be easily fashioned out of material that is usually in stock and without the necessity of employing other tools or personnel than is available at such stations.

In order to explain the nature of the present invention a few embodiments thereof will be described and the theory underlying the invention explained without intending to limit the invention by such disclosure. As will be obvious to those skilled in the art the invention may find various other embodiments without departing from the spirit thereof as defined in the claims.

The drawings illustrate a few of the many pos-

sible variants of the invention, only so much being shown as is necessary for one skilled in the art to understand. The drawings are purely schematic and are not constructed to any scale. The relative lengths and spacing of the conductors should, therefore, be determined in accordance with the description and not the drawings.

Fig. 1 illustrates a network associated with a transmission line and capable of matching a load impedance to a surge impedance at one frequency, and presenting a substantially infinite impedance at another predetermined frequency;

Fig. 2 shows two such impedances bridged across the transmission line;

Fig. 3 shows a concentric conductor arranged to perform the functions of the network shown in Fig. 1;

Fig. 4 shows a modification of Fig. 1;

Fig. 5 is the concentric conductor equivalent of Fig. 4;

Fig. 6 shows another modification of Fig. 1;

Fig. 7 is the concentric conductor equivalent of Fig. 6;

Fig. 8 is a third modification of the arrangement shown in Fig. 1;

Fig. 9 is the concentric conductor equivalent of Fig. 8;

Fig. 10 is a variant of Fig. 2;

Figs. 11 and 11A are two modifications of Fig. 2 in which two transmitters are connected with the transmission line through two branches;

Fig. 12 illustrates the application of Fig. 11 to a system using three transmitters;

Figs. 13 and 14 illustrate the application of Figs. 1 and 2 to networks for a system through which currents of three frequencies are transmitted;

Fig. 15 is a modification of Fig. 14 and an extension of Fig. 10 to a three frequency system;

Fig. 16 is a modification of Fig. 1;

Fig. 17 shows the application of Fig. 16 to a three frequency system;

Fig. 18 shows a four frequency system in which the networks of Figs. 16 and 17 are used; and

Figs. 19 and 20 are graphs for facilitating the calculation of values.

For the sake of simplicity, it is assumed that the spacing of the transmission line and other network wires is uniform throughout.

Let us assume a network (Fig. 1) consisting of a two-wire transmission line T, with a loop of wire ACEFDB bridged across it, and a loop of wire bridged across this loop at points CD. The distance from AB to CD is Q, from CD to EF, S, and from CD to GH, P. High frequency alter-

nating current is fed to the transmission line at 1, 2.

Let Z_{AB} be the impedance at AB at some frequency f . This impedance may be expressed in terms of the surge or wave impedance of the line z_0 , wavelength λ and the lengths of the various parts of the network shown in Fig. 1.

Let

$$p = \frac{2\pi P}{\lambda}, s = \frac{2\pi S}{\lambda}, \theta = \frac{2\pi Q}{\lambda} \text{ where } \lambda = \frac{c}{f}$$

where c is velocity of light and where P , Q and S are lengths defined in Fig. 1.

Then the impedance of section CDEF (looking into the section from above) is $jz_0 \tan s$. The impedance of section CDGH (looking from CD towards GH) is $jz_0 \tan p$. The impedance ξ of the two sections in parallel is given by

$$\frac{1}{\xi} = \frac{1}{jz_0} \left(\frac{1}{\tan s} + \frac{1}{\tan p} \right)$$

$$\xi = jz_0 \frac{\tan s \cdot \tan p}{\tan s + \tan p}$$

It is known that a section of line of any length L terminated into an impedance, say ξ at the far end has impedance

$$Z = \frac{z_0^2 - jz_0 \xi \cot \frac{2\pi L}{\lambda}}{\xi - jz_0 \cot \frac{2\pi L}{\lambda}} \quad (1)$$

Applying this formula to the present case, by putting $\xi = \xi$ and $L = Q$, we get,

$$Z_{AB} = \frac{z_0^2 - jz_0 \xi \cot \theta}{z_0 \xi \tan s + \tan p - jz_0 \cot \theta}$$

$$Z_{AB} = -jz_0 \tan p + \tan s + \tan s \tan p \cot \theta \quad (2)$$

Inasmuch as Z_{AB} is always a pure imaginary we may simplify calculations which follow by putting

$$\frac{Z_{AB}}{Z_0} = yj \quad \text{(so that } y \text{ is the absolute value of } \frac{Z_{AB}}{Z_0})$$

Introducing y we get

$$y = -\frac{\tan p + \tan s + \tan s \tan p \cot \theta}{\tan s \tan p - (\tan s + \tan p) \cot \theta} \quad (3)$$

For later reference it will be convenient to solve this equation for $\cot s$, thus expressing s in terms of other quantities. This yields

$$-\cot s = \cot p + \frac{y + \cot \theta}{1 - y \cot \theta} \quad (4)$$

Let us now consider the behaviour of the network shown in Fig. 1 at two frequencies f_1 and f_2 . Let

$$\lambda_1 = \frac{c}{f_1}; \lambda_2 = \frac{c}{f_2}$$

be the wave lengths which correspond to the two frequencies f_1 and f_2 . If we make

$$P = \frac{\lambda_1}{2} \text{ and } Q = \frac{\lambda_2}{4}$$

then Z_{AB} at frequency f_2 will be infinite regardless of the value of S . Indeed, we have

$$\theta = \frac{2\pi \lambda_2}{4\lambda_2} = \frac{\pi}{2}; \cot \theta = 0$$

therefore,

$$y = -\frac{\tan p + \tan s}{\tan s \tan p} = -(\cot p + \cot s)$$

If we now let P approach

$$\frac{\lambda_2}{2}$$

then p approaches π and $\cot p$ approaches $\pm\infty$. Therefore, no matter what the value of S is, y approaches $\pm\infty$, provided that we exclude the special case $\cot s = \infty$. When $\cot p$ approaches $\pm\infty$ and $\cot s = \infty$, y is indeterminate and therefore the impedance is mathematically indefinite and in practice unstable. Since $Z_{AB} = jz_0 y$, Z_{AB} becomes infinite when y does. Thus we see that any section with

$$P = \frac{\lambda_2}{2}, Q = \frac{\lambda_2}{4}$$

has an infinite Z_{AB} at $f = f_2$.

At any other value of f , however, Z_{AB} is not infinite but has some other value which depends on the value of S . Moreover, S may be adjusted so that Z_{AB} is given any desired value at any prescribed frequency $f = f_1$.

Indeed at $f = f_1$ we have

$$p = p_1 = \frac{2\pi \lambda_2}{2\lambda_1} = \frac{\pi \lambda_2}{\lambda_1}$$

$$\theta = \theta_1 = \frac{2\pi \lambda_2}{4\lambda_1} = \frac{\pi}{2} \frac{\lambda_2}{\lambda_1}$$

$$p_1 = 2\theta_1$$

and

$$-\cot s_1 = \cot p_1 + \frac{y + \cot \theta_1}{1 - y \cot \theta_1} \quad (5)$$

It may be observed from this that s_1 and hence S , may be calculated for any value of

$$y = \frac{1}{j} \frac{Z_{AB}}{z_0}$$

That is, given a desired value of Z_{AB} at f_1 , we may always calculate from (5) the corresponding value of s_1 , and therefore S , which will give the prescribed Z_{AB} . The network of Fig. 1, will, therefore, at frequency f_1 offer any desired value of reactance, and at the same time with P and Q chosen as above present an infinite impedance at frequency f_2 .

On account of this property of network, it may, in accordance with the present invention, be used at two different frequencies as an impedance matching means between the transmission line supplying a load having an arbitrary impedance. The network may be precomputed to perform said function without the necessity of varying its constants by switching means or the like when the frequency of the alternating current is changed. It will perform its function when both frequencies are simultaneously impressed on the transmission line.

For the purpose of matching a transmission line to a load in accordance with the present invention two networks like the one shown in Fig. 1 may be employed. This is illustrated in Fig. 2 in which a high frequency radio transmitter is connected with an antenna by means of the transmission line T . The two networks are joined to the transmission line at A_1B_1 and at A_2B_2 . When the frequency f_1 is impressed on the line then, with both networks removed, waves will be reflected from the antenna if the impedance of the latter is not equal to the surge impedance of the line. A standing wave pattern will result from the interference of waves traveling towards and away from the antenna so that at certain points on the line currents of large and at other

points currents of small amplitude will be observed. There will be places of maximum and minimum currents.

The location of junction A_1B_1 will be chosen with reference to a point at which minimum current occurs on the line. Let l_1 be the distance between said point and the juncture and q_1 be the ratio of minimum and maximum current on the line section between the juncture and the antenna. If the transmission line is short, q_1 will be the ratio of minimum-maximum current all along the line with networks I and II in Fig. 2 removed. If the line is long (of the order of fifty wave lengths) then the ratio of minimum-maximum currents will vary along the line, and in this case the ratio should be determined in the neighborhood of the proposed location of the juncture.

If the line were cut at the point where maximum current occurs and the impedance looking into the section of the line connected to the load is measured, the impedance will be found to be a pure resistance of some value R_1 . If the line were cut at a point a quarter wave length away (towards the transmitter), i. e., where the current is minimum, the impedance (looking towards the load) will also appear to be a pure resistance of some value R_2 .

In accordance with the law applicable to quarter wave transformer R_1 , R_2 and z_0 (the surge impedance of the line) are related in the following manner:

$$R_2 = \frac{z_0^2}{R_1} \quad (6)$$

Since we may assume that the power dissipated in a quarter wave length of the transmission line conductors is very small, equal amounts of power will pass through said points where the transmission line was assumed to be cut. We may, therefore, write

$$I^2_{max}R_1 = I^2_{min}R_2 \quad (7)$$

Multiplying Equations 6 and 7 we obtain after reduction

$$R_1 = z_0 q_1 \quad (8)$$

This resistance may, therefore, be substituted for the section of the line between the load and the maximum point, without disturbing the state of standing waves on the line between the maximum point and the transmitter.

Assuming now that the line is cut at a distance l_1 from R_1 towards the transmitter, the impedance looking towards the load is given by Equation 1. Replacing ξ by R_1 and L by l_1 we get

$$Z = \frac{z_0^2 - jz_0 R_1 \cot \frac{2\pi l_1}{\lambda_1}}{R_1 - jz_0 \cot \frac{2\pi l_1}{\lambda_1}} \quad (9)$$

If a pure imaginary impedance of value jx is bridged across the impedance Z given by (9), the two impedances will result in a new impedance Y given by

$$\frac{1}{Y} = -\frac{j}{x} + \frac{1}{Z}$$

If x and Z are so chosen that Y is equal to z_0 , the transmission line will be terminated into its surge impedance. Therefore, if l_1 and x are so chosen that

$$\frac{1}{z_0} = -\frac{j}{x} + \frac{R_1 - jz_0 \cot \frac{2\pi l_1}{\lambda_1}}{z_0^2 - jz_0 R_1 \cot \frac{2\pi l_1}{\lambda_1}} \quad (10)$$

then the problem of impedance matching at one frequency is solved.

Equating separately the real and imaginary parts of Equation 10 we derive after replacing R_1 by $z_0 q_1$ (8)

$$1 = q_1 \frac{1 + \cot^2 \frac{2\pi l_1}{\lambda_1}}{1 + q_1^2 \cot^2 \frac{2\pi l_1}{\lambda_1}} \quad (11)$$

10 and

$$\frac{z_0}{x} = \frac{(q_1^2 - 1) \cot \frac{2\pi l_1}{\lambda_1}}{1 + q_1^2 \cot^2 \frac{2\pi l_1}{\lambda_1}} \quad (12)$$

Solving (11) for

$$\cot \frac{2\pi l_1}{\lambda_1}$$

20 we get

$$\cot \frac{2\pi l_1}{\lambda_1} = \frac{1}{\pm \sqrt{q_1}}$$

Substituting this value into (12) we obtain

$$\frac{z_0}{x} = \frac{q_1 - 1}{\pm \sqrt{q_1}}$$

and therefore

$$\tan \frac{2\pi l_1}{\lambda_1} = \pm \sqrt{q_1} \quad (13)$$

therefore,

$$l_1 = \frac{\lambda_1}{2\pi} \tan^{-1}(\pm \sqrt{q_1}) \quad (13A)$$

35 and

$$\frac{x}{z_0} = \frac{\mp \sqrt{q_1}}{1 - q_1} \quad (14)$$

Equation 13 enables us to find the two possible places for the juncture A_1-B_1 at which the matching network I must be connected to the line. Equation 14 gives the value of the impedance which this network must have in order to perform its function as an impedance matching network. The value of s may now be found from (4) in which y is to be replaced by

$$\frac{x}{z_0}$$

50 given by (14).

Thus we get

$$s_1 = \cot^{-1} \left\{ -\cot p - \frac{\mp \frac{\sqrt{q_1}}{1 - q_1} + \cot \theta}{1 \pm \frac{\sqrt{q_1}}{1 - q_1} \cot \theta} \right\}$$

55 Since

$$s = \frac{2\pi S}{\lambda_1}$$

60 the length of the free end of the loop is given by

$$65 S = \frac{\lambda}{2\pi} \cot^{-1} \left\{ -\cot p - \frac{\mp \frac{\sqrt{q_1}}{1 - q_1} + \cot \theta}{1 \pm \frac{\sqrt{q_1}}{1 - q_1} \cot \theta} \right\} \quad (15)$$

65 When

$$P = \frac{\lambda_2}{2}$$

and

$$Q = \frac{\lambda_2}{4}$$

and the network I is to match the impedance at frequency f_1 , the length of the free end S_1 will be given by

$$S_1 = \frac{\lambda_1}{2\pi} \cot^{-1} \left(-\cot \frac{\pi\lambda_2}{\lambda_1} - \frac{\frac{\mp\sqrt{q_1}}{1-q_1} + \cot \frac{\pi\lambda_2}{2\lambda_1}}{1 \pm \frac{\sqrt{q_1}}{1-q_1} \cot \frac{\pi\lambda_2}{2\lambda_1}} \right) \quad (15A)$$

At frequency f_2 , the second frequency at which the transmitter may be operated, the network I presents infinite impedance at A_1B_1 and has no effect whatever on the line.

This will be apparent from Equation 2 and from the discussion following Equation 4.

The surge impedance of the transmission line will, therefore, not be matched at frequency f_2 and a second network II must be provided for this purpose.

The location of A_2B_2 as well as the length of the free end S_2 of the second network are found in the same manner as explained in connection with network I. However, in this instance the distance from A_2B_2 to the place of minimum current is measured at frequency f_2 and in Equation 15A λ_2 and λ_1 are interchanged. Consequently

$$S_2 = \frac{\lambda_2}{2\pi} \cot^{-1} \left(-\cot \frac{\pi\lambda_1}{\lambda_2} - \frac{\frac{\mp\sqrt{q_2}}{1-q_2} + \cot \frac{\pi\lambda_1}{2\lambda_2}}{1 \pm \frac{\sqrt{q_2}}{1-q_2} \cot \frac{\pi\lambda_1}{2\lambda_2}} \right) \quad (15B)$$

The formula corresponding to 13A will be

$$l_2 = \frac{\lambda_2}{2\pi} \tan^{-1}(\pm\sqrt{q_2}) \quad (13B)$$

In Equations 13B and 15B q_2 is the ratio of minimum-maximum currents at frequency f_2 .

In practice it will be convenient to impress on the line first frequency f_1 and then frequency f_2 before the networks I and II are bridged across the line. The positions of current maxima should be noted, and the ratios (q_1 and q_2) of current minima to maxima at each of the two frequencies should be determined. Then the locations of junctions A_1B_1 and A_2B_2 are determined from 13A and 13B, and the lengths S_1 and S_2 calculated from 15A and 15B. When the two networks thus precomputed are connected to the line, they will be approximately right and will require only minor adjustments to compensate for the disturbances introduced by such factors as insulators, impedance of wires used to short, and other factors secondary in nature and, therefore, not taken into account in the formulae.

Fig. 3 illustrates a modification of the network illustrated in Fig. 1. Instead of the usual two-wire transmission line, a concentric tube type of transmission line is used in which a conductor 30 is centrally located within and insulated from a tube 31 of conducting material. The impedance matching network instead of loops of wire consists of concentric conductors 32, 33 and 34, 35. 32 and 33 are bridged across 30 and 31, and 34 and 35 across 32 and 33. The free ends are interconnected at 36 and 37. When the two networks like the one shown in Fig. 3 are used in the manner indicated in Fig. 2, they will function in the same manner as networks I and II.

The location of the junctions, as well as the lengths P, Q and S are determined in the same manner as above described provided that the insulation used does not change the propagation velocity of electric waves along the line. Other-

wise λ_1 and λ_2 must in the formulae be multiplied by the ratio of the actual velocity to the velocity of light.

In the network shown in Fig. 4, the closed loop CDGH of Fig. 1 is replaced by two parallel wires C₄G₄ and D₄H₄. The length of each wire will be one-half the length of P (Fig. 1). If used in the combination shown in Fig. 2, this length will be

$$\frac{\lambda_1}{4}$$

for one and

$$\frac{\lambda_2}{4}$$

for the second network. If for any reason P (Fig. 1) is made longer than half a wave length, the D₄H₄ and C₄G₄ must be made shorter than

$$\frac{\lambda}{4}$$

In general, the relation between the length L_c of a closed loop and the length L_o of an open loop which may be used in place of one another is given by the following equation

$$L_o = \frac{\lambda}{4} + L_c \pm N \frac{\lambda}{2} \quad (16)$$

in which N is any integral number or zero, and λ is the wavelength at which the two are equivalent.

When as in Fig. 4, D₄C₄G₄H₄ is open at the end and is made

$$\frac{\lambda_2}{4}$$

in length the impedance looking into C₄D₄H₄G₄ from terminals C₄D₄ is not $jz_0 \tan p$, as in the case of closed loop in Fig. 1, but $-jz_0 \cot p$. Therefore in this case in Equation 3 for y we must replace $\tan p$ by $-\cot p$. Solution of Equation 3, so modified, yields the following value of $\cot s$:

$$-\cot s = -\tan p + \frac{y + \cot \theta}{1 - y \cot \theta} \quad (4A)$$

Thus, when the loop C₄D₄H₄G₄ is open as in Fig. 4 Equation 4A and not Equation 4 should be used for calculating the value of s .

Fig. 5 shows a concentric conductor arrangement and bears the same relationship to Fig. 4 as Fig. 3 bears to Fig. 1.

In the arrangement shown in Fig. 6 the closed loop AEFB of Fig. 1 is replaced by two parallel open-ended wires A₆E₆ and B₆F₆. All values of such networks are computed in the manner shown in connection with Figs. 1 and 2 except the length S₆.

Fig. 7 is the concentric conductor counterpart of Fig. 6.

Fig. 8 shows a matching network consisting of two open-ended pairs of wires A₈E₈ and B₈F₈, and C₈G₈ and D₈H₈. The lengths of these open-ended pairs of wires P₈ and S₈ and other values are determined in accordance with the theory applicable to Fig. 4 together with Equation 16.

Fig. 9 shows a network built up of concentric conductors in the manner of Fig. 8.

Fig. 10 shows a simplified arrangement which can perform the same function as the arrangement shown in Fig. 2. These two arrangements, however, are not equivalent. While network I in Fig. 2 has infinite impedance and therefore does not disturb the line at wave length λ_2 , network I in Fig. 10 has a finite impedance at λ_2 and changes the state of standing waves along the portion of the transmission line between the junction A₁₂B₁₂ and the transmitter. Consequently,

the length of the free end S_{10} as well as the location of the junction $A_{11}B_{11}$ of network II must be determined with reference to the standing wave pattern at wave length λ_2 which results after network I has been connected, and not with reference to the state of standing waves at wave length λ_2 which exists when all networks are removed.

In network II P_{10} is made

$$\frac{\lambda_1}{2}$$

and

$$Q_{10}, \frac{\lambda_1}{4}$$

so that at wave length λ_1 the impedance looking into network II at $A_{11}B_{11}$ is infinite. Therefore at wave length λ_1 network II does not effectively exist, and the impedance of the transmission line T_{10} is matched into the antenna load by means of network I.

Referring now to Fig. 11, the transmission line T_{10} , the antenna and the networks I₁₁ and II₁₁ are arranged in the same manner as in Fig. 2. The line T_{11} is connected through line extension or branches 50 and 51, respectively, with T_1 and T_2 , two transmitters operating on wave lengths λ_1 and λ_2 . Networks III₁₁—V₁₁ are bridged across branches 50 and 51.

V_{11} is a loop of wire

$$\frac{\lambda_2}{2}$$

in length and bridged across 50 at any convenient point other than

$$\frac{\lambda_2}{2}$$

or multiple thereof, from JJ. At wave length λ_2 this loop acts as a short across the line and prevents the currents of this wave length from disturbing the normal operation of T_1 .

Similarly III₁₁ is a loop of wire

$$\frac{\lambda_1}{2}$$

in length, also bridged across 51 at any convenient point (other than

$$\frac{\lambda_1}{2}$$

or multiple thereof) for the purpose of preventing currents of wave length λ_1 from interfering with T_2 .

VI₁₁ is a loop of wire bridged across 50 between T_1 and V_{11} . This network is used to match the surge impedance of the line coming from the transmitter T_1 to the impedance of the section of the line disturbed owing to the presence of V_{11} , junction JJ and III₁₁. Electrical waves sent out from T_1 will be reflected back towards the transmitter from the junction of V_{11} , III₁₁ as well as JJ, and loop VI₁₁ is provided to prevent the propagation of these waves back into the transmitter and to turn this power into the antenna.

If q_1 is the ratio of minimum to maximum currents of wave length λ_1 between T_1 and V_{11} , then the distance between a current maximum and the juncture of VI₁₁ measured towards T_1 is given by Equation 13A. Since the impedance looking into a closed loop is

$$jz_0 \tan \frac{2\pi L}{\lambda}$$

where L is the length of the loop, in view of Equation 14 the length of VI₁₁ will be

$$\frac{\lambda_1}{2\pi} \tan^{-1} \left(\frac{\mp \sqrt{q_1}}{1-q_1} \right)$$

Loop IV₁₁ performs the same function as VI₁₁ and is precomputed in the same manner.

Fig. 11A shows a modification of Fig. 11 in which the transmission line extensions 50, 51 leading to the two transmitters are bridged each by one impedance so constructed as to block the line extension at one, and so as not to disturb the line at the other wave length.

The extension 50 is bridged by a horizontal loop at a distance of

$$\frac{\lambda_2}{4}$$

20. from the junction of the main transmission line. At a distance of

$$\frac{\lambda_2}{2}$$

25. from the junction with 50, the loop is bridged by a vertical loop

$$\frac{\lambda_2}{2}$$

30. in length. Therefore, the junction of 50 and the loop will be effectively short-circuited at wave length λ_2 . The free end S_{11A} is adjusted so that the impedance of the network is infinite at wave length λ_1 .

The construction of the network bridged across line 51 will be obvious from the above and the notations appearing on the drawings.

The arrangement shown in Fig. 11 may be used also when more than two transmitters are associated with the line. An arrangement for three transmitters is shown in Fig. 12.

The networks I₁₂, II₁₂ and III₁₂ bridged across the line T_{12} function in the same manner as the networks of Figs. 13 and 14. Three transmitters T_{11} , T_{21} and T_{31} are connected with T_{12} through branches 100, 101, 102. Three networks are bridged across each branch.

Loops 103 and 104 short circuit the line 100 at wave lengths λ_2 and λ_3 , respectively, and loop 105 matches the surge impedance of the branch at wave length λ_1 . The positioning values and function of these loops are the same as those discussed in connection with Fig. 11. The fact that we now have two half-wave loops 103 and 104, instead of one, does not interfere with the freedom of choosing their locations.

The loops 106—108 and 109—111 perform the same functions with respect to T_{21} and T_{31} as loop 103—105 performs with respect to T_{11} .

In accordance with the present invention the network can be constructed so as to match impedance where currents of more than two frequencies are transmitted. Fig. 13 illustrates such network by means of which lines carrying three frequencies can be accommodated.

A loop of wire 60 is bridged across the transmission line T_{13} at $A_{13}B_{13}$. The distance from A_{13} and B_{13} to 61 and 62 is

$$\frac{\lambda_1}{4} + n \frac{\lambda_1}{2}$$

where n can be either zero or any integral whole number. The choice of n depends upon the value of λ_2 in comparison with λ_1 . This section

must be long enough to permit the connection of a loop 70 at 63, 64 at a distance

$$\frac{\lambda_2}{4}$$

5

from A₁₃B₁₃.

At 61, 62 a loop 80

$$\frac{\lambda_1}{2}$$

10

in length is connected with loop 60.

The free end S₁₃ of loop 60 is made of such length that the impedance looking into the loop at A₁₃B₁₃ with loop 70 removed is infinite at wave length λ_2 . At λ_1 it is infinite owing to the length of loops 80 and 60.

Loop 70 bridged across 60 at 63, 64 is

$$\frac{\lambda_1}{4}$$

15

in length from 63, 64 to 71, 72. Loop 75 bridged across 70, at 71, 72 is

$$\frac{\lambda_1}{2}$$

in length. The free end of 70 beyond 71, 72 is of such length that the impedance of the network at A₁₃B₁₃ is adjusted to the proper value for matching the load to the surge impedance at wave length λ_3 .

Since the impedance at 63, 64 looking into loop 70 is infinite at λ_1 , loops 60 and 80 behave at λ_1 as though 70 were removed. Therefore, the impedance of the whole network is infinite at λ_1 . At λ_2 63, 64 occur at a voltage node along 60 (since 63 and 64 are at a distance of

$$\frac{\lambda_2}{4}$$

40

from B₁₃ and A₁₃ as mentioned above) because the impedance at 63, 64 looking towards 61, 62 had been made zero for λ_2 by the adjustment of S₁₃. On this account, the addition of network 70, 75 does not disturb the functioning of 60, 80. The impedance at A₁₃B₁₃ is therefore infinite at λ_2 .

The presence of the whole network bridged across A₁₃B₁₃ will have no effect on the transmission line at λ_1 and λ_2 , and at the same time the network will have the prescribed impedance at λ_3 .

The values of the constants of this network as well as the positioning of junction points A₁₃B₁₃ may be precomputed substantially along the lines discussed in connection with Figs. 1 and 2.

Fig. 14 illustrates three networks like the one shown in Fig. 13 connected with a transmission line T₁₄ through which a transmitter is connected with an antenna.

The network I₁₄ is adjusted to match the impedance of the line at wave length λ_1 and have infinite impedance at λ_2 and λ_3 . Similarly, II₁₄ matches at λ_2 and III₁₄ at λ_3 and present infinite impedance at the other two frequencies. All considerations applicable to Fig. 2 and also Fig. 13 apply here also.

Fig. 15 is a modification of Fig. 14 and the network disclosed therein performs the same function as the one disclosed in the former. By providing a network III₁₅ in addition to the networks I₁₅ and II₁₅, which correspond to the two balancing networks shown in Fig. 10, the transmission line T₁₅ may be used for three different frequencies. The network III₁₅ is like the network shown in Figs. 13 and 14. It consists of

four loops of wire 79, 80, 85 and 88. The length of loop section from A₁₅B₁₅ to junction points 83, 84 of loop 80 is

$$\frac{\lambda_2}{4}$$

the length of the loop section from A₁₅B₁₅ to junction points 86, 87 of loop 88 is

$$\frac{\lambda_1}{4} + n \frac{\lambda_1}{2}$$

The loop 88 is

$$\frac{\lambda_1}{2}$$

in length, the loop section from 83, 84 to 81, 82 is

$$\frac{\lambda_1}{4}$$

and the length of loop 85 is

$$\frac{\lambda_1}{2}$$

25 The free end S₁₅ of loop 79 is adjusted in the same manner as the free end S₁₃ of the network shown in Fig. 13 and the free end of loop 80 is adjusted in the same manner as the free end of loop 70.

The positioning and proportions of the three networks will be the same as discussed in connection with Figs. 13 and 14 and Fig. 10.

The sections or networks may also be constructed in the manner illustrated in Figs. 16-18. The method of generating sections explained in connection with these figures is particularly applicable to the use of triple, quadruple, etc., sections, as well as to double sections.

The impedance element shown in Fig. 16 is so proportioned that looking into it at 200, it is of infinite impedance at λ_2 as well as at λ_1 . This is accomplished by making loop portion 200-201 of length

$$\frac{\lambda_2}{4}$$

45 loop 201-202

$$\frac{\lambda_2}{2}$$

and loop 201-203 of a length to be hereinafter stated in greater detail.

Since 201-202 is

$$\frac{\lambda_2}{2}$$

55 the loop 200-203 is at λ_2 , effectively short-circuited at 201. Section 200-201, being

$$\frac{\lambda_2}{4}$$

60 when current of this wave length flows, at terminals 200 will present infinite impedance. From what has been said in connection with the previous figures, it will be clear that in order to present at 200 infinite impedance when the wave length is λ_1 , y at $S=S_{15}$ must be ∞ . This occurs when the denominator of (3) is zero. Putting this equal to zero and solving for $\tan S_{15}$ we get after some reduction

$$\tan \frac{2\pi S_{15}}{\lambda_1} = \frac{\sin \frac{2\pi \lambda_2}{2\pi \lambda_1}}{1 - \cos \frac{2\pi \lambda_2}{2\lambda_1}}$$

75

From this it follows that the length S_{16} of loop 201—203 is equal to

$$\frac{\lambda_1}{2\pi} \tan^{-1} \left(\frac{\sin \frac{\pi \lambda_2}{\lambda_1}}{1 - \cos \frac{\pi \lambda_2}{\lambda_1}} \right)$$

If the loop of Fig. 16 is made longer and the cross connection moved from 203 to 205 then, as shown in Fig. 17, by connecting a

$$\frac{\lambda_1}{2}$$

loop across points 203, the network will not only appear at 200 as an infinite impedance when current of λ_1 and λ_2 wave lengths flow, but the impedance at 203 may be made to have any prescribed value at wavelength λ_3 and thus may be employed to match impedances at this wavelength.

By lengthening the free end of loop 200—205 and adding a third horizontal loop (see IV₁₈ of Fig. 18)

$$\frac{\lambda_3}{2}$$

in length, the network may be made to have infinite impedance at λ_1 , λ_2 and λ_3 and match the load to the surge impedance at λ_4 .

Further extensions of the system will be obvious from the above.

Fig. 18 illustrates the use of fixed networks I₁₈—IV₁₈ constructed as explained in connection with Figs. 16 and 17 and permanently bridged across the transmission line T₁₈ to match the antenna load impedance to the surge impedance when currents of λ_1 , λ_2 , λ_3 , λ_4 wavelengths are impressed upon the line.

Here as in Figs. 2, 10, 11, 12, 14 and 15, each impedance together with the line conductors between it and the antenna are used as the sole impedance matching means. No adjustable or specially built and protected devices need be provided and the construction and installation may be effected by the usual operating personnel of a radio station. Charts or graphs may be prepared for ready reference in the construction of networks herein described. Fig. 19 shows, for example, a curve useful in selecting proper values for a network like the one illustrated in Fig. 16.

The numbers in the first vertical column represent values of S in degrees for the end section 201—203 short-circuited at 203. The abscissa is calibrated for

$$p = 2\theta = \frac{\lambda_2}{\lambda_1}$$

also in degrees.

Thus when it is necessary to proportion a network like the one shown in Fig. 1, in such a manner that it will have a substantially infinite impedance at two wavelengths (as is done in Fig. 16) we need only to make loop 201—202 of length

$$\frac{\lambda_2}{2}$$

calculate

$$p = 180 \frac{\lambda_2}{\lambda_1}$$

degrees, find corresponding S from Fig. 19 in degrees and make loop 201—203 of length

$$\frac{s}{360} \lambda_1$$

In Fig. 19 the curve is not extended beyond the point $\lambda_1 = \lambda_2$. When $\lambda_2 > \lambda_1$ p comes out greater than 180°. In this case 180° may be deducted from the value of p and the chart used in the manner mentioned above because of the well known periodic properties of tan s.

In Fig. 20 is shown a diagram which may be used to simplify calculations of networks like the one shown in Fig. 4. In order to explain the use of this figure let us put $y = \tan \psi$ in Equation 4A. After this substitution Equation 4A may be transformed into the following: $\cot s = \tan p - \cot(\theta - \psi)$ once the value of y has been determined by means of

$$y = \pm \frac{\sqrt{q}}{1 - q}$$

See Equation 14. The auxiliary angle ψ as well as values of $p = 0$ may be readily obtained from

$$\frac{\lambda_2}{\lambda_1}$$

by means of Fig. 20. In this figure the straight line oP is provided for this purpose. The actual calculation of p from

$$\frac{\lambda_2}{\lambda_1}$$

consists of looking up in the right column of Fig. 20, marked

$$\frac{\lambda_2}{\lambda_1}$$

the given value of

$$\frac{\lambda_2}{\lambda_1}$$

following a horizontal line from this value of

$$\frac{\lambda_2}{\lambda_1}$$

to the left to the point where this line intersects line oP and, reading off the value of p which is the abscissa of this point.

Since in the network in Fig. 16, $\theta = p$, both values are obtained at one time. The auxiliary angle ψ is determined from y by means of curves marked "tan p." The value of y is found in the left column of this figure and a horizontal line is followed to the point of intersection with the nearest tan p curve. The abscissa of this point of intersection is the desired value of ψ . Once p, and $\theta - \psi$ are determined, the values of $\tan p$ and $\cot(\theta - \psi)$ are obtained by means of $\tan p$ and $\cot(\theta - \psi)$ curves and values of $\cot s$ is deduced by algebraic subtraction. The value of s is read off by means of the $\cot s$ curves. Since

$$s = \frac{2\pi S}{\lambda}$$

the value of S is then given by

$$S = \frac{360}{360} \lambda$$

What is claimed is:

1. In combination, a transmission line, two sources of alternating current of different frequencies, connections between said sources and the line, a load connected to the end of the line, fixed impedance devices permanently bridged across the first connection between the first source and the line effectively short-circuiting the connection at the frequency of the second source, compensating for the short-circuiting action of the impedance devices across the second connection, and preventing the reflection of

waves into the first source, and fixed impedance devices permanently bridged across the second connection between the second source and the line effectively short-circuiting the connection at the frequency of the first source, compensating for the presence of the impedance devices across the first connection, and preventing the reflection of waves into the second source.

2. In combination, a transmission line, two sources of alternating current of different frequencies, connections between said sources and one end of the line, a load connected to the other end of the line, fixed impedance devices permanently bridged across various sections of said line, each substantially matching the load impedance to the surge when current of a different frequency is impressed on the line, and presenting substantially infinite impedance at other frequencies, impedance devices permanently bridged across the first connection between the first source and the line effectively short-circuiting the connection at the frequency of the second source, compensating for the short-circuiting action of impedance devices bridged across the second connection, and preventing the reflection of waves into the first source, and impedance devices permanently bridged across the connection between the second source and the line effectively short-circuiting the other connection at the frequency of the first source, compensating for the presence of the impedance devices across the first connection, and preventing the reflection of waves into the second source.

3. In combination, a transmission line, two sources of high frequency alternating current of different frequencies, connections between said sources and one end of the line, a load connected to the other end of the line, a fixed impedance device permanently bridged across one section of said line substantially matching the load impedance to the surge impedance when current of one frequency is impressed on the line, and presenting substantially infinite impedance at the other frequency, a second fixed impedance device permanently bridged across another section of said line substantially matching the load impedance to the surge impedance when current of the other frequency is impressed on the line and presenting

substantially infinite impedance at said one frequency, a third fixed impedance device permanently bridged across the connection between the first source and the line effectively short-circuiting the connection at the frequency of the second source, compensating for the short-circuiting action of the fourth impedance device and preventing the reflection of waves into the first source, and a fourth fixed impedance device permanently bridged across the connection between the second source and the line effectively short-circuiting the connection at the frequency of the first source, compensating for the presence of the third impedance device, and preventing the reflection of waves into the second source.

4. In combination, a first transmitter of one frequency, a second transmitter of another frequency, a main transmission line, an antenna connected to said main line, a two-conductor line connecting each transmitter to said transmission line, and an impedance circuit in shunt across each of said two-conductor lines, each of said impedance circuits being constructed and arranged to provide at its point of connection to its two-conductor line, a high impedance to the flow of energy in its associated two-conductor line of the frequency of its associated transmitter and a low impedance to the flow of energy in its associated line of the frequency of the other transmitter, the shunt impedance circuit across one two-conductor line being located from the junction of said one two-conductor line with the main transmission line a distance equal to an odd multiple of one-quarter of the wave generated by the transmitter connected to the other two-wire line, said other shunt impedance circuit being located from the junction of said other two-conductor line with the main transmission line a distance equal to an odd multiple of one-quarter of the wave generated by the transmitter connected to said one two-conductor line, and means connected across said main transmission line between said junction and said antenna for matching the antenna to the characteristic impedance of the main transmission line for the different frequencies of said two transmitters.

ANDREW ALFORD.
